UNITED STATES PATENT OFFICE.

FREDERICK W. MURRAY, OF FAIRFAX, VIRGINIA, ASSIGNOR TO THE MILLER TRAIN CONTROL CORPORATION, OF STAUNTON, VIRGINIA, A CORPORATION OF VIRGINIA.

HYDRAULIC GOVERNOR.

Application filed June 13, 1923. Serial No. 645,151.

To all whom it may concern:

Be it that I, FREDERICK W. MURRAY, a citizen of the United States, residing at Fairfax, in the county of Fairfax and State of Virginia, have invented certain new and useful Improvements in Hydraulic Governors, of which the following is a specification.

This invention relates to hydraulic governors, and more particularly to a speed 10 governor controlled by the volume of liquid delivered by a pump connected to a movable part of the vehicle, the speed of which is to be controlled.

An object of the invention is to provide 15 an apparatus consisting of a cylinder, a piston in the cylinder, the cylinder having an opening controlled by an adjustable valve providing a constant leak of fluid, and being further provided with a variable opening 20 controlled by the movement of the piston whereby a greater amount of fluid is delivered from the cylinder as the piston rises to take care of the increased volume of fluid admitted at higher speeds.

25 The piston is provided with a piston rod projecting from the cylinder which may be connected to any suitable mechanism to apply brakes, cut off the feed of fuel, or control the speed in any other desired way. 30 For the purpose of illustration, I have shown the apparatus connected to a train control system of the type described and claimed in the patent to William B. Murray, granted June 7, 1921, No. 1,380,578. The piston rod 35 is adapted to control the opening of a valve which is connected to a pressure cylinder forming a part of the train control system whereby the engineer's brake valve is operated by the reduction of pressure in the 40 pressure cylinder.

In the accompanying drawings, I have shown several embodiments of the invention. In this showing:

45 Figure 1 is a side elevation of a portion of a locomotive and tender having a train control system arranged thereon and showing the governor applied,

Figure 2 is a vertical sectional view through the governor mechanism on line 2—2 50 of Figure 1,

Figure 3 is a vertical sectional view on an enlarged scale of a metering tube which cooperates with the piston to increase the size of the opening when the piston rises.

55 Figure 4 is a vertical sectional view on

line 4—4 of Figure 2, parts being being shown broken away,

Figure 5 is a detail view of a cylinder connected to the pressure cylinder of the train control system,

Figure 6 is a horizontal sectional view on line 6—6 of Figure 2,

Figure 7 is a side elevation of the cylinder shown in Figure 5 of the drawings and the mechanism associated therewith,

Figure 8 is a horizontal sectional view on line 8—8 of Figure 2,

Figure 9 is a detail view of a solenoid armature and the parts associated therewith,

Figure 10 is a perspective view of a supplemental cam and latching mechanism therefor,

Figure 11 is a side elevation showing the mechanism within the upper cylinder or casing looking in the opposite direction from Figure 2, the casing being shown broken away,

Figure 12 is a view similar to Figure 11 looking in the opposite direction,

Figures 13 to 16 are detail sectional views 80 of different forms of metering tubes,

Figure 17 is a side elevation, partly in section, of the train controlling system, to which the device is applied,

Figure 18 is a front elevation, partly in 85 section, of a shoe by means of which the train controlling apparatus is actuated,

Figure 19 is a vertical sectional view on line 19—19 of Figure 18, and,

Figure 20 is a diagrammatic view illustrating the electric circuit.

Referring to Figures 1 and 17 of the drawings, the reference numeral 1 designates generally a locomotive having a tender 2 secured thereto in the usual manner. The

locomotive and tender are adapted to travel on tracks 3. The locomotive is provided with the usual engineer's air brake valve 4,

having an operating handle 5. A drum or pulley 6 is rotatably mounted on the top 100 of the valve casing and is provided with an arm 7 extending behind the handle or lever

5, whereby rotation of the drum will turn the handle and set the brakes. A pressure cylinder 8 is arranged adjacent the air

brake valve and is connected to the air tank by means of a pipe 9. As shown, the pipe 9 communicates with a passage 10 extending to the top of the cylinder. The upper end

105 of the cylinder is closed by a head 11 having 110

a central boss 12. A piston 13 is arranged within the cylinder and this piston is provided with a piston rod 14 extending through the boss 12. The piston rod is adapted to be surrounded by suitable packing 15 held in position by a packing gland 16 and a packing nut 17. As shown, the packing nut engages threads formed on the exterior of the boss 12. The inner end of the boss 10 is surrounded by a suitable strip of packing 18. A bracket 19 is supported on the top of the cylinder and a steel roller 20 is journaled on a pin 21 carried by this bracket. A chain 22, preferably formed of steel, is connected to the piston rod. As shown, the piston rod is provided with a slot 23, in its upper end, and one end of the chain is secured in this slot by means of a rivet 24 or other suitable fastening element. The end 20 of the chain is secured to the drum 6, arranged on the top of the air brake valve. A bracket 25 is secured to the casing of the air brake valve, and extends upwardly. The brackets 19 and 25 are adapted to receive and support a cover plate 26 arranged over the chain and drum.

A valve casing 27 is arranged adjacent the cylinder 8. This valve casing is provided with a main inlet passage 28 extending through the cylinder wall to the bottom and communicating with the interior of the cylinder through a port 30. The piston 13 is provided with a restricted port 31 whereby the lower portion of the cylinder communicates with the upper portion to normally establish a balanced pressure therein. The valve casing is provided with a main valve seat 32 arranged in a port 33 connecting the main inlet passage to a chamber 34. This chamber is provided with an outlet 35 communicating with a pipe or conduit 36. The bottom of the chamber is closed by a plate 37 having an opening 38 therein. The upper end of this opening is provided with a valve seat 39 and a port 40 extends through the plate 37 to a secondary chamber 41. A whistle 42 is arranged on the valve casing and communicates with the secondary chamber 41. A valve member 43 is arranged in the valve casing and is provided with a valve 44, adapted to engage the valve seat 32. The lower end of this member is provided with a valve 45, adapted to engage the valve seat 39. The valve member is provided with a downwardly projecting valve stem 46 which extends through the opening 38. The main valve 44 is normally in the open position shown in Figure 17 of the drawings and is adapted to be controlled by a solenoid 47. This magnet is provided with a core 48 which is raised when the magnet is energized. A guide 49 is supported in the upper portion of the magnet and a pin 50 extends through this guide. When the core of the magnet is raised, this pin is lifted

to engage the valve stem 46 and close the valve 44. The core of the magnet is provided with a depending portion 51 projecting from the bottom of the magnet casing to permit manual operation of the valves.

The upper portion of the valve casing is provided with a port 52 communicating with a transverse port 53 in the top of the cylinder. The valve casing is closed by a cap 54, the interior of which is hollow, forming an auxiliary chamber 55. This chamber is provided with a small bleed opening 56 that extends into the main outlet port 35 and thus communicates with the conduit or pipe 36. A port 57 extends inwardly beyond the bleed opening 56 and communicates with a passage 58 extending into the chamber 55. The upper end of this passage is provided with a valve seat 59 and a valve 60 is normally in engagement with this seat. The valve is provided with a downwardly projecting stem 61, extending into the main inlet passage 28, and this stem is adapted to be engaged by an extension 62 of the main valve when the main valve is raised. The upper end of the valve 60 is provided with an extension 63 which is received in a recess 64 in the cap.

Referring in detail to Figures 18 and 19 of the drawings, the pipe or conduit 36 communicates with a shoe arranged on a portion of the locomotive or tender and adapted to engage inclined ramps disposed at spaced intervals along the track. When the shoe is raised, the lower end of the pipe is open to the atmosphere. The pipe or conduit may be formed of sections of hose or other flexible material to permit ease of removal and these sections are connected to each other by couplings 65 of any desired type. The shoe is mounted on a bracket 66 which, as shown in Figure 1 of the drawings, is illustrated as mounted on the tender 2. The bracket is arranged relatively close to the ground whereby the shoe will be engaged by a ramp extending a slight distance above the ground. As shown, the shoe comprises a substantially cylindrical member 67 having flanges 68 formed on opposite sides. These flanges are provided with slots 69 to permit adjustment of the shoe in assembling. Bolts 70 pass through these openings and are received in the bracket 66. These bolts are retained in position by means of nuts 71. Suitable insulation may be arranged between the shoe and the bracket to insulate the shoe from the vehicle. The shoe is provided with a removable cap 72 which is retained in position by means of bolts 73. These bolts pass through a flange 74 formed on the bottom of the cap and are received in openings in the body portion of the shoe, the piston being provided with suitable packing 76 to prevent leakage of air. A coil spring 77 is arranged between the top

of the piston and the cap. The conduit 36 communicates with a port 78 arranged in an enlargement 79 of the shoe. This port communicates with the interior of the shoe by means of a transverse port 80. As shown, the end of the port 80 is closed by a plug 81. The shoe is further provided with an outlet opening 82.

The piston is provided with a piston rod 83, the lower portion of which is enlarged, as at 84. An L-shaped plate 85 is secured to the lower end of the piston rod by means of bolts 86 and nuts 87. The L-shaped plate 85 is provided with a horizontal portion 88. A flange 89 is arranged at one end of the horizontal portion of the plate. Similar flanges 90 are arranged on opposite sides of the plate. A shoe 91 formed of hard metal is supported beneath the plate 88 between the side flanges 90 and abutting the flange 89. A removable plate 92 is arranged opposite the flange 89 and bolts 93 are passed through the shoe, the plate 92 and the flange 89 to retain the insert plate 91 in position. Nuts 94 are arranged on the ends of these bolts. The piston is provided with a longitudinal port 95 extending downwardly from the top and a ball valve 96 is arranged in the lower portion of this port. The ball valve is normally retained in closed position by a spring 97.

The speed control mechanism consists of an upper casing 98 and a governor casing or cylinder 99. The casing 98 is open to the atmosphere and is connected to the pressure cylinder by means of a pipe 99' and a branch pipe 100. This branch pipe communicates with a valve casing 101 arranged within the casing 98 having a valve seat 102 formed at its outlet end. A valve 103 engages this seat and is normally retained in a closed position by means of a spring 104. It will be apparent that when the valve 103 is opened, the pressure in the pressure cylinder 8 will be lowered and the piston 13 lowered in the cylinder to operate the engineer's air brake valve.

The hydraulic governor cylinder 99 forms a reservoir for oil, water, or other fluid preferably kerosene oil, employed in the governor and an operating cylinder 105 is arranged therein. The operating cylinder is arranged within the reservoir for convenience of construction and for protection, but this feature of construction is not essential and the invention is in no way limited thereto. The lower end of the outer cylinder or reservoir is closed by a plate 106 and this plate is provided with an inlet passage 107 communicating with the operating cylinder, through a port 108. The outer end of the passage 107 is connected to a pipe 109 (see Figure 1) through a union or coupling 110. This pipe is connected to the outlet side of a pump 111 mounted on the vehicle and driven from an

axle 112 by a chain 113. The pump may be of any standard construction of the unidirectional type whereby the fluid will flow in one direction regardless of the direction in which the vehicle travels. The inlet end of the pump is connected to a pipe 114 which communicates with the reservoir 99, as indicated at 115 (see Figure 8). A piston 116 is arranged within the operating cylinder of the governor and this piston is provided with a piston rod 117 extending through the cylinder head and through a guide 118 into the casing 98 of the speed control mechanism.

The piston rod is surrounded by a spring 119 which normally tends to hold it in lowered position. A packing ring 119' is arranged on the bottom of the piston to retain it spaced from the bottom of the operating cylinder, and thus provide a passage 80 through the cylinder at all times. The lower end of the piston rod is provided with a recess or cut-out portion 120 adapted to receive a metering tube 121 shown in detail in Figure 3 of the drawings. As shown, the metering tube is tapered toward its upper end. A ring 122 is secured to the piston and surrounds the metering tube, the inner face of the ring being beveled as at 123, and being adapted to snugly fit the tube adjacent its lower end when the piston is at the bottom of the cylinder. At spaced intervals, the metering tube is provided with projecting rings 124 and 125, for a purpose to be described. The operating cylinder is provided with an outlet port 126 communicating with a passage 127 in the plate 106. The outer end of this passage is closed by a plug 128. The passage communicates with a tube 129 extending into the reservoir to a point adjacent its top. A threaded valve member 130 extends through the top of the reservoir in alignment with the end of the tube 129. This valve member is adapted to be locked in a desired position by means of a nut 130. The metering tube is supported in a threaded sleeve 132 arranged within a reduced portion 133 formed on the lower end of the operating cylinder and received in an opening 115 in the plate 106. The lower end of the sleeve 132 is closed by a plug 134. The metering tube is provided with a plurality of openings 135 communicating with a circumferential groove 136 formed in the sleeve 132. This groove in turn communicates with a port 137 in the reduced portion of the operating cylinder 133 and this port communicates with a passage 138 extending radially through the plate 106. The outer end of the passage 138 is closed by a plug 139. This passage is connected to a tube 140 extending into the reservoir and having openings 141 formed therein adjacent the top of the reservoir. The operating cylinder is further provided with an emergency outlet 142 com-

municating with a passage 143 in the plate 106. The end of this passage is closed by a plug 144. This passage communicates with a tube 145 extending upwardly in the reservoir to a point adjacent its top. A plug 146 is arranged in the head of the reservoir in alignment with the tube 145 and this plug is provided with a recess adapted to receive a coil spring 147. A ball valve 148 is arranged beneath the spring 147 and normally engages the end of the tube 145 to close it.

Within the casing of the speed control mechanism, the piston rod 117 is surrounded by a sleeve 149 which as shown, is slightly spaced therefrom. The sleeve 149 is secured to the piston rod by means of a pin 150 and is adapted to move therewith. A second sleeve 151 is arranged in the space between the piston rod and the sleeve 149 and this second sleeve is secured to the casing by means of bolts 152. The inner sleeve is provided with a slot 153 adapted to receive a pin 154 carried by the outer sleeve whereby the piston rod and its associated parts are prevented from rotating. A main cam 154' is carried by the outer sleeve 149 and this cam is engaged by a roller 155 mounted on the end of a bell crank lever 156. A spring 157 is arranged beneath the other end of the bell crank lever to normally maintain the roller in engagement with the cam. As shown, the bell crank lever is pivotally mounted on a pin 158 supported in a suitable bracket 159 extending upwardly from the bottom of the casing 98. The lower end of the cam is provided with a high portion 160 which is adapted to engage the roller 155 when the piston and piston rod move upwardly due to an increased speed and swing the bell crank lever on its pivot to depress the free end of the bell crank lever. As shown (see Figure 2), this end of the bell crank lever engages the stem of the valve 103 to open the valve when the lever is swung on its pivot and apply the brakes.

An auxiliary pressure cylinder 161 is mounted in the casing 98 and is connected to the main pressure cylinder 8 of the train control mechanism through the pipe 99 and a branch pipe 162 whereby pressure is maintained in the cylinder 161 equal to the pressure in the bottom of the cylinder 8. A piston 163 is arranged in the cylinder. A piston rod 164 is connected to the piston and extends through the cylinder head 165. The piston rod is surrounded by a coil spring 166 which forces the piston downwardly in the cylinder when the pressure is lowered. The upward movement of the piston is limited by a plate 167 secured to the piston and projecting through a slot 168 in the cylinder wall. An arm 169 is secured to the upper end of the piston rod and a lever 170 is pivotally connected to this arm. The lower end of this lever is received in a

well 171 and the lever is normally forced toward the front of the well by a spring 172. The lever is provided with a slot 173 having a shoulder 174 formed therein. An auxiliary cam 175 is secured to a pivot pin 176, arranged in a recess in the main cam 154'. The pin 176 projects beyond the side of the main cam and is provided with an arm or lever 177, having a pin or lug 178 formed thereon. This lug is arranged in the slot 173 and is adapted to be engaged by the shoulder 174 (see Figure 7). When the fluid is exhausted from the main pressure cylinder 8 and the auxiliary pressure cylinder 161, the downward movement of the piston 163 causes the arm 177 to rotate the pin 176 and move the auxiliary cam 175 to the dotted line position shown in Figure 2 of the drawings, whereby only slight upward movement of the piston rod 117 is necessary to swing the bell crank lever 156 on its pivot and open the valve 103. If the speed of the locomotive is sufficient to have raised the piston before the fluid is exhausted, the engagement of the roller 155 with the auxiliary cam 175 will retain the valve 103 in open position until the speed of the locomotive is reduced to the minimum speed.

The supplemental cam is adapted to be retained in an operative position by means of a latch 179 mounted on a pin 180. This pin is rotatably mounted in the main cam and is provided with a sleeve 181 on one end carrying a depending pin 182. A solenoid 183 is arranged within the casing and this solenoid is provided with a core or armature 184. The armature is normally maintained in raised position by means of a spring 185 but is moved downwardly against the tension of the spring when the armature is energized. An arm 186 is secured to the armature and this arm is secured to a shaft 187 journaled in a suitable bearing or bracket 188 on the top of the solenoid whereby the shaft will be revolved when the armature is operated. An arm or crank 189 is secured to the end of the shaft 187 and the side of this arm is provided with a projecting finger or lug 190. The arm 189 is provided with a laterally offset lower end 191. Arm 192 is pivotally connected to the arm 189 by means of a pin 193 and is arranged substantially parallel thereto. This arm is provided with a laterally offset end 194 overlying the offset end 191. The offset end 194 is provided with an opening 195 to receive the arm or pin 182 and return the latch 179 to an inoperative position when the magnet 183 is energized. A yoke 196 is secured to the other end of the shaft 180 and this yoke is adapted to engage a lever 197 when the latch is in operative position. As shown, the lever 197 is pivotally mount-

ed in a bracket 198 and retained in operative position by a spring 199.

In Figures 13 to 16, I have shown several alternate forms of metering tubes which 5 may be used in place of the tube 121. In Figure 13, I have shown a tube 200, the outer wall of which tapers at a uniform rate throughout its length. In Figure 14, I have shown a similar tube 201 provided 10 with spaced series of openings 202. In the form of the invention shown in Figure 15 of the drawings, there is provided a tube 15 of varying tapers. As shown, the tube is provided with surfaces 203, 204, 205 and 206, which are successively smaller in diameter than the adjacent lower surfaces and which taper upwardly. In Figure 16 of the drawings, I have shown a tube 207 having spaced circumferential grooves 208.

20 Referring to Figure 20 of the drawings, a ramp 209 is arranged beside the track 3, the ramp being positioned at a suitable braking distance in front of the block to be controlled thereby and is energized when 25 the block is clear and deenergized when the block is occupied by another train or when the track circuit of the block is open for any other reason. As shown, a ramp circuit is provided consisting of a source of current 30 210, having suitable lead wires 211 connected thereto. A relay 212 is arranged in the track circuit (not shown) and controls a switch 213 in one of the lead wires 211. This lead wire is connected to the ramp 35 and the other lead wire is connected to the track. A lead wire 214 connects the shoe and the solenoid 183. This solenoid is arranged in series with the solenoid or magnet 47 of the train stopping mechanism. The 40 solenoid 47 is in turn grounded on the frame of the locomotive by means of a wire 215.

The operation of the train stopping mechanism is substantially similar to that described in Patent No. 1,380,578 and will be 45 briefly described. When the shoe is raised by a ramp, the piston moves upwardly in the cylinder 67 and permits communication between the chamber 81 and the outlet 82. If the ramp is deenergized, the valve 44 re- 50 mains in an open position and the fluid is exhausted from the bottom of the pressure cylinder 8, lowering the piston and moving the handle 5 of the engineer's air brake valve to an operative position. Normally the fluid 55 from the reservoir delivered to the pressure cylinder through the pipe 9 passes through the opening 31 in the piston to provide a balanced pressure in the cylinder 8 and build up a pressure in the pipe 36. When an energized ramp is passed, the valve 44 engages 60 the valve seat 32 preventing the pressure in the cylinder from being lowered and the brakes are not applied.

In normal operation, the pump 111 de- 65 livered fluid to the operating cylinder of the

governor through pipe 109 and passage 107. The outlet end of the tube 129 provides a constant leak from the operating cylinder which may be controlled by the threaded

70 plug 130, thus permitting a variation of the minimum speed of the train. As the speed of the train increases, the volume of fluid delivered to the operating cylinder of the governor is greater and the piston is raised in

75 the cylinder 105. This increase in flow is taken care of by the metering tube 121.

When the piston is in its lowermost position, the ring 122 barely engages the exterior of the metering tube whereby substantially no liquid passes through the recess 120 of the piston into the top of the metering tube. The tapered surface of the metering tube provides an opening of increasing diameter, as the piston moves upwardly. The liquid

80 passes through the metering tube to the groove 136 of the pipe or cylinder 132 and thence to the reservoir through the passage 138 and the pipe or tube 140. The rings 124 and 125 temporarily decrease the size of the

85 opening provided by the metering tube and give an impetus to the upward movement of the piston when these points are reached. The tube may be provided with rings of this character at any desired point, such as at

90 the minimum speed of the train and at the maximum speed at which the train is designed to run. When the piston moves upwardly a sufficient distance, the high point

95 160 of the main cam 154 engages the roller 155 of the bell crank lever 156, swinging it on its pivot and opening the valve 103. As

100 the chamber 101 is connected to the pressure cylinder 8 by means of pipes 99 and 100, the opening of valve 103 releases the fluid in the bottom of the pressure cylinder and applies

105 the brakes in the manner heretofore described. It will thus be seen that the upward movement of the piston provides a speed controlled automatic stop which may be regulated to operate at any desired speed.

110 The auxiliary cam forms a part of the train stopping mechanism and is moved to an operative position after passing a de-energized ramp to prevent the engineer

115 from running the train above a minimum speed during the next block. When the train passes a deenergized ramp and the fluid is exhausted from the pressure cylinder 8, the fluid in cylinder 161 is also exhausted caus-

120 ing the piston 163 to be lowered by the spring 166. This moves the arm downwardly and the engagement of the lug 178 and the shoulder 174 swings the auxiliary cam on its pivot to the dotted line position,

125 whereby it will engage the roller 155 at a materially lower speed, such as a speed of 30 miles per hour, and open the valve 103.

If the speed of the locomotive is above the minimum speed when the auxiliary cam is 130 moved to an operative position, the roller

155 remains in engagement with the cam and the valve 103 is retained in an open position until the speed decreases to a point where the roller and cam are disengaged, thus preventing the engineer from releasing the brakes and proceeding at a rate of speed above the minimum speed. When the auxiliary cam moves to an operative position, the latch 179 is moved, by gravity, to the operative position shown in Figure 10 of the drawings. When the train reaches an energized ramp indicating normal track conditions ahead, the solenoid 183 is energized and the shaft or pin 187 revolved by the downward movement of the armature 184. This moves the arms 189 and 192 in a counter-clockwise direction (see Figure 9) and swings the latch 179 to an inoperative position. When the latch is in an operative position, the yoke 196 is in a substantially horizontal position, as shown in Figures 10 and 12. If the sleeve 149 and cam 154' are raised by an increase in speed, the yoke will be raised above the upper end of the arm 198. When the cam descends, due to a decrease in speed, the yoke engages the upper end of the lever 198 to swing the yoke and shaft 180 in a counter-clockwise direction and return the latch 179 to an inoperative position.

When the metering tube shown in Figure 13 of the drawings is employed, there is a constant increase in the size of the opening between the metering tube and the ring 122, as the piston moves upwardly. By providing the openings 202, as shown in Figure 14 of the drawings, the upward movement of the piston is retarded when the rings approach these openings, and the leakage through these openings causes a slower movement of the ring after the openings have been passed. When a metering tube of the form shown in Figure 15 of the drawings is employed, the opening between the ring and the tube increases constantly as the piston travels over any one surface. When the end of one surface is reached, the movement of the piston is retarded due to the uneven increase in the size of the opening and further upward movement of the piston does not take place until the speed becomes proportionate to the increased size of the opening. The junction of two surfaces may be arranged at a point where the movement of the piston is to be retarded for a desired purpose. Such as a point corresponding to the minimum speed or maximum speed. When the metering tube is provided with the grooves 208, the movement of the piston is retarded as the ring passes the grooves, but the piston moves at its former rate of speed as soon as the ring is above the grooves.

It is to be understood that the form of the invention herewith shown and described

is to be taken as a preferred example of the same, and that various changes in the shape, size, and arrangement of parts may be resorted to without departing from the spirit of the invention or the scope of the sub- 70 joined claims.

I claim:

1. A hydraulic governor comprising a casing, a movable member mounted therein and adapted to be actuated by fluid passing 75 through said casing, means controlled by the apparatus to be governed to vary the volume of fluid delivered to said casing, said casing being provided with an outlet of constant size, and means controlled by 80 the movement of said movable member to permit additional discharge from said casing in varying amounts.

2. A hydraulic governor comprising a casing, a movable member mounted therein 85 and adapted to be actuated by fluid passing through said casing, means controlled by the apparatus to be governed to vary the volume of fluid delivered to said casing, said casing being provided with an outlet of 90 constant size, means for adjusting the size of said outlet, and means controlled by the movement of said movable member to permit additional discharge from said casing in varying amounts.

3. A hydraulic governor comprising a casing having an outlet of constant size, a piston mounted in said casing, said casing being provided with a second outlet varying in size according to the position of said 100 piston, a pump connected to a part of the apparatus to be controlled, a reservoir arranged adjacent said casing, and connections between said reservoir, said pump, and said casing.

4. A hydraulic governor comprising a casing having an outlet of constant size, means for adjusting the size of said outlet, a piston mounted in said casing, said casing being provided with a second outlet varying in size according to the position of said 110 piston, a pump connected to a part of the apparatus to be controlled, a reservoir arranged adjacent said casing, and connections between said reservoir, said pump, and said casing.

5. A hydraulic governor comprising a cylinder, a piston mounted in said cylinder, said cylinder being provided with an outlet of constant size, the lower face of said piston being provided with a recess, a tapered metering tube arranged in the bottom of said cylinder and extending into said recess, and a ring carried by said piston and surrounding said tube.

6. A hydraulic governor comprising a cylinder, a piston mounted in said cylinder, said cylinder being provided with an outlet of constant size, the lower face of said piston being provided with a recess, a meter- 130

ing tube arranged in the bottom of said cylinder and extending into said recess, said metering tube being tapered toward its upper end, a ring carried by said piston and surrounding said metering tube whereby the discharge of liquid through said tube will increase as the piston is raised in said cylinder, and means for varying the rate of increase in the discharge of liquid through 10 said tube.

7. A hydraulic governor comprising a reservoir, a cylinder arranged within said reservoir, and communicating therewith, a piston mounted in said cylinder, a pump 15 operatively connected to a part of the apparatus to be governed and adapted to deliver fluid to said cylinder, said cylinder being provided with an outlet of constant size, said piston being provided with a recess in 20 its lower face, and a metering tube extending into said recess.

8. In a hydraulic governor, a cylinder, a reservoir surrounding said cylinder, a piston mounted in said cylinder, said cylinder being provided with an inlet opening, 25 said cylinder being further provided with an outlet opening arranged adjacent the bottom, a tube connected to said outlet opening and extending into said reservoir to a point adjacent the top thereof, and additional means for discharging fluid from 30 said cylinder into said reservoir, said additional means being variable and being controlled by the position of the piston in the 35 cylinder.

9. In a hydraulic governor, a cylinder, a reservoir surrounding said cylinder, a piston mounted in said cylinder, said cylinder being provided with an inlet opening, 40 said cylinder being further provided with an outlet opening arranged adjacent the bottom, a tube connected to said outlet opening and extending into said reservoir to a point adjacent the top thereof, the lower 45 face of said piston being provided with a recess, and a metering tube arranged in the bottom of said cylinder and extending into said recess, said metering tube communicating with said reservoir.

50 10. A hydraulic governor for locomotives comprising a casing, a movable member mounted therein and adapted to be actuated by fluid passing through said casing, means

controlled by the speed of the locomotive to vary the volume of fluid delivered to said 55 casing, said casing being provided with an outlet of constant size, means controlled by the movement of said movable member to permit additional discharge of fluid from 60 said casing in varying amounts, and means controlled by the movement of said movable member for applying the brakes of the locomotive when a predetermined speed is reached.

11. A hydraulic governor for locomotives 65 comprising a casing having an outlet of constant size, a piston mounted in said casing, said casing being provided with a second outlet varying in size according to the position of said piston, a pump connected to 70 said locomotive, a reservoir arranged adjacent said casing, connections between said reservoir, said pump, and said casing, and means controlled by the movement of said piston to apply the brakes of said locomotive 75 when a predetermined speed is reached.

12. A hydraulic governor for locomotives comprising a cylinder, a piston mounted in said cylinder, said cylinder being provided with an outlet of constant size, the lower 80 face of said piston being provided with a recess, a tapered metering tube arranged in the bottom of said cylinder and extending into said recess, a ring carried by said piston and surrounding said tube, means 85 for delivering fluid to said cylinder in amounts varying in accordance with the speed of the locomotive, and means controlled by the movement of said piston for applying the brakes of the locomotive when 90 a predetermined speed is reached.

13. A hydraulic governor comprising a chamber through which fluid is adapted to pass and having a movable wall, means 95 controlled by the apparatus to be governed to vary the amount of fluid delivered to said chamber, said movable wall being adapted to alter its position according to the volume of fluid delivered to said chamber whereby the volume of said chamber changes, and 100 means for increasing the rate of discharge of fluid from said chamber as the volume thereof increases.

In testimony whereof, I affix my signature.

FREDERICK W. MURRAY.
